HOSE DISPLAY PACKAGE

Robert D. Kahn, Rockville Centre, N.Y., assignor to Fedtro, Inc., Long Island City, N.Y., a corporation of New York

Filed Apr. 28, 1967, Ser. No. 6,885

Term of patent 14 years

Int. Cl. D9—04
U.S. Cl. D9—191

FIG. 1

FIG. 2

FIG. 1 is a plan view of my design for a hose display package; and

FIG. 2 is a side elevational view thereof.

The characteristic feature of my design resides in the specific configuration of the three restraining straps, namely, their undulating hill and valley shape with an elongated raised ridge thereon.

I claim:

The ornamental design for a hose display package, substantially as shown and described.
